CONDENSER CONSTRUCTION

Franklin S. Smith, Brooklyn, N. Y.

Application May 25, 1931, Serial No. 539,810

51 Claims. (Cl. 175—41)

This invention relates to electric condenser construction and more particularly to a condenser construction adapted to operate in connection with alternating current circuits of relatively high potential.

One of the objects of this invention is to provide an electric condenser construction that will be simple, thoroughly practical, and of dependable and efficient action in use. Another object is to provide a condenser construction characterized by inexpensive manufacture, ease of assembly, and rapid manufacture. Another object is to provide an electric condenser of strong and rugged and compact construction and capable of long-continued service in practical use. Another object is to provide a condenser construction adapted to operate particularly in connection with alternating current circuits substantially noiselessly and free from excessive vibration. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings in which is shown one of various possible embodiments of my invention,

Figure 1 is a vertical central sectional view of an assembled condenser, certain parts being shown in elevation;

Figure 2 is a horizontal sectional view, on an enlarged scale, as seen substantially on the line 2—2 of Figure 1;

Figure 3 is a view as seen from the bottom of Figure 1, assuming the bottom of the container or casing to be removed, showing particularly the end plate of the condenser construction;

Figure 4 is a fragmentary plan view, on an enlarged scale, as seen substantially along the line 4—4 of Figure 1, of certain details of part of the insulating structure;

Figure 5 is a horizontal sectional view, on an enlarged scale, as seen substantially on the line 5—5 of Figure 1; and

Figure 6 is a schematic sectional view, certain parts being shown exaggerated, through an assembled condenser unit, and may be assumed to be taken along the line 6—6 of Figure 5 after completion of assembly of the unit of Figure 5.

Similar reference characters refer to similar parts throughout the several views in the drawings.

Referring now to the drawings, there is shown at 10 a tank or casing preferably of a cylindrical shape and made sufficiently strong to withstand relatively high pressures; conveniently the tank 10 and the closure member 11 at the upper end thereof are made of pressed steel. Within the casing 10, closed by the end or closure member 11, is contained the condenser construction.

The electric condenser may be, insofar as certain features of my invention are concerned, of any suitable construction, but preferably is made up of interleaved condenser plates of metal foil insulated by interposed sheets of solid dielectric, such as paper, with which coats a dielectric medium to achieve certain important practical advantages, in a manner to be more clearly described hereinafter. Preferably, also, the condenser is made up in units.

A preferred form of condenser unit and, moreover, one embodying certain other features of my invention, I build up substantially as follows:— Referring to Figure 5 I have there shown in plan view and superimposed one upon the other and alternated with each other a metal foil plate member 50, an insulating sheet of solid dielectric 51, and another metal foil plate member 52, shaped substantially as shown in Figure 5. Where the tank or casing is of round cross-section, I preferably make the paper insulating sheets 51 substantially square, the four sides being indicated at 51^a, 51^b, 51^c and 51^d, but preferably the corners are cut off as is indicated at 51^e, 51^f, 51^g and 51^h.

Foil plate members 50 and 52 are the same shape and typify the other foil plate members, any suitable number of which go to make up a single unit, members 50 constituting one electrode and members 52 constituting the other electrode of the condenser unit. The foil members are shaped to have a width less than the width of the paper member 51 and a length greater than the other dimension of the interposed paper sheet 51. Considering the shape of the metal foil members in detail, foil member 50 has two opposite side edges 50^a and 50^b adapted, when superimposed upon paper sheet 51, to fall well within the side edges 51^d and 51^b, respectively, of the paper sheet 51. The other two side edges 50^c and 50^d of foil member 50 are spaced apart sufficiently so that marginal side portions of foil member 50 materially overlap the side edges 51^c and 51^a of the paper sheet 51, but these overhanging marginal portions are centrally cut away as at 50^e and 50^f so as to form tabs A, B, C and D. At

its corners, metal foil member 50 is diagonally cut as at E. The peripheral or marginal relations between the foil member 50 and the paper sheet 51 are clearly shown in Figure 5.

- 5 Foil member 52 is shaped exactly like foil member 50 but when alternated with the foil member 50 with the paper sheet 51 interposed therebetween, it is turned through 90° so that its four tabs F, G, H and K appear as shown in Figure 5.
- 10 A suitable number of foil members and paper insulating members, like members 50, 51 and 52 of Figure 6, are alternated to build up a single condenser unit and by way of illustration I have shown in Figure 6 three foil members 50 alternated with three foil members 52 with insulating paper sheets 51 interposed therebetween, but it is to be understood that any suitable number may be thus employed. After having superimposed and alternated these members, the overhanging tabs A, B, H, K, D, C, G and F (see Figure 5) are then bent together, as is shown in Figure 6 in section with respect to the overhanging tabs K of Figure 5, whereby all of foil plates 50 are electrically interconnected by tabs A, B, D and C and all of foil plate members 52 are interconnected by tabs H, K, G and F.

A suitable number of condenser units are then stacked one upon the other, and if desired the units may be connected in series or may be connected in series-multiple or in any other suitable way to meet the particular electrical conditions met with in practice, and if desired suitable solid dielectric insulating members may be interposed between adjacent condenser units or between groups of condenser units, depending upon how the units are inter-connected and depending upon the voltage differences against which adjacent units are to be insulated. In Figure 1 I have indicated the stack of condenser units as a whole at 12, individual condenser units being indicated at 12^a and solid dielectric sheets or plates interposed between certain of the units I have indicated at 12^b. Such interposed solid dielectric members 12^b as need be employed are preferably given a shape when viewed in plan similar to that of the paper insulating sheet 51 of Figure 5.

The stack 12 is interposed between upper and lower clamping metal members 13 and 14, generally circular in shape and suitably ribbed to give them substantial rigidity, and between these clamping members 13 and 14, the condenser stack construction 12 is tightly compressed, as in a hydraulic press, to a pressure on the order of 50 300 pounds per square inch, whereupon the clamping members 13 and 14 are held and tied together by a suitable number of tie rods or bolts 15 illustratively shown (see Figure 2) as four in number and preferably uniformly distributed 55 about the periphery of the end frame members. These tie rods or bolts 15, in coaction with the rigid construction of the end frame members 13 and 14, securely hold the aligned condenser units in assembled relation and insure that the foil plates of the units and the sheet insulation interleaved therewith are maintained tightly compressed. The resultant condenser construction is thus rigid, compact and mechanically strong.

Suitable solid insulating material is interposed 70 between the ends of the stack structure 12 and the respective clamping members 13 and 14 and in Figure 1 I have illustrated this solid insulation in the form of a suitable sheet 16 of solid dielectric material interposed between the upper end of the 75 stack 12 and the clamping member 13, a similar

solid dielectric member being interposed between the lower end of the stack 12 and the bottom clamping member 14.

The clamping members 13 and 14 are preferably round but are preferably dimensioned, with respect to the inside diameter of the casing 10, so that they may be received within the latter but with substantial clearance between their peripheral portions and the inside walls of the casing 10, as will be clear from Figures 1 and 3; this clearance is for the purpose, among others, to prevent contact transmission of vibration from stack 12 to casing 10. Also, the condenser stack construction 12, made up of plate or foil members and sheet insulation, preferably in units or sections 12^a, is of such configuration and dimensions that ample insulating clearance is obtained between it and the tank 10 and bolts 15.

The closure member 11 is shaped to have a peripheral side flange 11^a dimensioned to be received within the upper open end of the container 10 and the flange 11^a is provided with pairs of diametrically opposed holes 11^b and 11^c, and 11^e and 11^f, the former pair being upon a diameter which is preferably at right angles to the diameter along which the latter pair is, as is clearly shown in Figure 2. Moreover, the holes 11^b and 11^c are positioned somewhat lower, as viewed in Figure 1, in the flange 11^a than are the holes 11^e and 11^f, for a purpose more clearly described hereinafter. The flange 11^a of the cover member 11 supports two cross bars 17 and 18, preferably round in cross-section, the ends of the bar 17 being fitted into the holes 11^b and 11^c and the ends of the cross bar 18 being received into the holes 11^e and 11^f. The vertical displacement of the two pair of holes is such that the cross bars 17 and 18 just clear each other, as is clearly shown in Figure 1. From these cross bars, the condenser construction above described is suspended and supported.

Considering now the manner in which the above-described condenser stack is supported from the cross rods 17 and 18, it might first be noted that the upper plate or frame member 13 which is preferably in the form of a metal casting has integrally formed therewith, substantially at its center, a sort of housing, generally indicated at 19, and substantially cubical in shape, having opposed side walls 19^b and 19^c and 19^e and 19^f closed by a top wall 19^a, the portion 125 of the plate 13 proper directly opposite the top wall 19^a (as viewed in Figure 1) being cut away to permit access to the interior of the housing-like portion 19 of the frame member 13.

The opposed side walls 19^b and 19^c are provided with holes 19^h and 19ⁱ, respectively, while the opposed side walls 19^e and 19^f are similarly provided with holes 19^k and 19^m. These holes in the opposed side walls of the housing member 19 are materially larger than the cross-section of 13 the cross rods 17 or 18.

Prior to the assembly of the upper frame member 13 with respect to the remaining parts of the condenser construction, there is inserted into the housing-like portion 19, through the opening in the plate member 13 directly opposite the top wall 19^a, a cube-like block 20, the latter being of materially smaller dimensions than the cube-like interior of the housing portion 19, and interposed between the interior walls of the portion 19 and the top and side walls of the block 20 is a yieldable or cushioning material preferably taking the form of felt padding indicated in Figure 1 at 21. This felt padding is of relatively tightly compacted felt of substantial thickness.

The block 20, which is preferably made of metal, is provided with two round holes 20^a and 20^b, the former being substantially in alignment with the holes 19^a and 19^b in the side walls 19^b and 19^c (see Figure 1) and the latter being substantially in alignment with the holes 19^c and 19^m in the side walls 19^e and 19^f (Figure 2). These two sets of aligned holes are displaced from each other in a vertical direction to substantially the same extent as are the opposed pairs of holes 11^b, 11^c and 11^e, 11^f, in the flange 11^a of the closure member 11. The housing-like portion 19, which thus forms a seat for receiving the block 20 but with the felt padding 21 interposed therebetween, is thereupon closed by means of the plate member 22 (Figures 1 and 2), the latter being secured to the under side of the plate member 13 by suitable screws and felt padding 23 being interposed therebetween and the under side of the block 20, as viewed in Figure 1. The end plate-like or frame member 13 is thereupon ready for assembly with respect to the remaining portions of the condenser construction, as has already hereinabove been described.

The condenser unit, thus made up of the plate construction 12 held in assembled relation between the end frame members 13 and 14 by the tie rods or bolts 15, and with the apertured block 20 seated within the housing portion 19, as above described, is then ready to be assembled with respect to the closure member 11. These two parts are thereupon so related to each other that the holes 11^b, 19^a, 20^a, 19^b and 11^c are substantially in alignment with each other, whereupon the cross bar 17 is threaded therethrough, the upstanding substantially circular reinforcing rib 18^a of the member 13 being provided also with suitable holes 13^b and 13^c (Figure 2) through which the cross bars 17 may pass with ample clearance. The layers of felt padding 21 are, of course, provided with suitable holes to pass the passage therethrough of the cross bar 17.

The cross bar 18 is thereupon threaded through the substantially aligned holes 11^c (see Figure 2), 19^k, 20^b, 19^m and 11^f, the reinforcing rib 18^a being again provided with suitable substantially aligned clearance openings 13^e and 13^f. The layers of felt padding 21 are again provided with suitable clearance holes through which the cross bar 18 may pass.

The cross bars 17 and 18 fit snugly within the holes in the flange 11^a of the cover 11 and also fit snugly into the holes 20^a and 20^b, respectively, in the block 20, while the various apertures in the parts of the end frame member 13 through which the cross bars pass are sufficiently large to provide ample clearance about the cross bars. Thus the cross bars are rigidly supported by the closure member 11 and the block 20 is rigidly held in position on these cross bars and substantially at the intersection thereof.

Strung onto and preferably uniformly distributed along the length of the tie bolts 15 are blocks 24 (see Figure 4) of solid dielectric material, such as molded bakelite, held in spaced relation by tubular members 25 of solid dielectric material, such as bakelite, these tubular members 25 being alternated with the insulating blocks 24 (Figure 1). These insulating blocks 24 fit in between the laterally spaced interconnected foil tabs; more specifically, members 24 fit into the recesses 50^a, 52^a, 50^b and 52^b (see Figure 5), respectively between connecting tabs A and B, H and K, D and C, and G and F, and thus the main body portions of the condenser stack are laterally

engaged on all four sides by these members 24 strung onto the four tie bolts 15. Moreover, as appears clearly from Figure 1, the vertical dimension of members 24 is such that the side portions of more than one condenser unit 12^a are engaged thereby. Thus, I provide against sagging or displacement of the condenser stack 12, particularly in case the ultimately assembled construction is laid over on its side.

The outer faces of the insulating blocks 24 are recessed, as at 24^a, to receive outwardly and radially projecting felt pads 26 adapted to contact with the inside wall of the casing 10 when the condenser construction is inserted into the latter. Also, members 24 are provided with ears 24^c and 24^d, preferably formed integrally therewith and appropriately recessed, as is clearly shown in Figure 4, so that suitable conductors 29 and 30, for example, (Figure 1) may be supported and dependably held in the alined ears. To these conductors, only two of which 29 and 30 are shown in the drawings, and any suitable number of which may be employed, the tabs of the individual condenser units, such as the tabs K of Figure 6, may be electrically connected where and as desired.

The bottom end plate member 14 is provided with a number of recesses 14^a, preferably uniformly distributed throughout its periphery, and projecting out of and radially from these recesses 14 are felt pads 27 also adapted to contact with the inside walls of the casing 10, as will be clear from Figure 3.

The lower face of the end frame member 14 is cross-ribbed, as at 14^b (Figure 3) to reinforce it mechanically and also to provide, between adjacent reinforcing ribs, a space for receiving one or more discharge coils 28, the latter comprising an iron core with a winding thereon and being of high impedance. The discharge coil is permanently connected across the terminals of the condenser so that when the condenser is disconnected from its circuit, its charge may be dissipated through the impedance of the discharge coil. Thus the stored energy of the condenser is dissipated through the impedance of the discharge coil and the voltage across the condenser reduced to zero, thereby eliminating any danger to an operator when the condenser is disconnected from its circuit. The latter is suitably insulated for the relatively high potential at which the condenser operates, and is secured to the end frame member 14 in any suitable manner.

Referring now to Figure 1, the cover member 11 is provided with suitable terminal insulators generally indicated at 28 and suitably constructed to carry the lead-in conductors 29 and 30, respectively, connected to the terminals of the condenser 12 through the wall of the cover 11, the terminals 28 being provided with suitable means exterior thereof for making electrical connection thereto.

The cover member 11 is provided with a suitable number of rings 31 by means of which the cover with the condenser construction suspended therefrom, all as above described, may be moved or lifted and then slid into the casing 10, bringing the felt pads 26 and 27 into coacting relation with the inside walls of the casing 10. The flanged portion 11^a of the cover 11 fits substantially snugly into the upper end of the casing 10, locking bars 17 and 18 against axial displacement, the upper peripheral portions of casing 10 being thereupon bent inwardly over the curved portion of the cover 11 and the two parts welded 159.

4
together, as is indicated at 32. The thus hermetically sealed casing 10-11 is thereupon connected to a suitable evacuating apparatus to pump out moisture and air, particularly such moisture and air as may be absorbed or occluded by the paper insulation of the condenser units, and is then filled with a gaseous dielectric under pressure, preferably taking the form of a substantially chemically neutral dry gas, nitrogen, for example, under a pressure on the order of fifteen atmospheres.

The condenser is then ready to be placed in circuit and may, for example, be connected to a relatively high tension alternating current transmission line, for the purpose, for example, of power factor correction. In use, the apparatus is preferably positioned so that its axis extends vertically and hence substantially in the position shown in Figure 1. When connected to a circuit of commercial frequency, condensers have a pronounced tendency to vibrate and hum, the hum sometimes assuming discomforting proportions. Where a gaseous dielectric and cooling medium is employed, as I prefer to employ it and by reason of which I achieve numerous advantages, certain of which are described hereinafter, there is little, if any, damping action upon the vibrating parts and the heavy metal casing acts as in the resonator, increasing the effect of the sound production. In accordance with certain features of my invention, however, I am enabled fully to achieve the unique and important advantages of the gaseous dielectric under pressure and at the same time eliminate the disadvantages due to this vibration and hum.

The condenser construction will be seen to be acoustically isolated from the tank 10-11, the weight of the condenser construction within the tank being transmitted to the latter through the felt padding 21 interposed between the block 20 and the interior walls of the housing portion 19 of the upper frame or clamping member 13, while direct mechanical contact between the side portions of the condenser construction and the sides of the tank 10 is prevented by the interposed yielding felt pads 26 and 27. Thus vibration is prevented from being transmitted from the condenser stack assembly 12 to the casing 10-11 though the assembly is dependably supported and held within the tank. Thus the tank or casing itself is precluded from being directly set into vibration to produce sound. On the other hand, any possible sound or hum that may be produced due to any possible vibration of the condenser stack assembly 12 or parts thereof not only is prevented from being transmitted to the enclosing tank but also is substantially muffled within the hermetically sealed casing itself.

Furthermore, should the assembled and completed construction be positioned on its side, the felt padding interposed between the block 20 and the walls of its seat 19 is still effective to function in the manner above described while the felt paddings 26 and 27, interposed between the condenser construction and the interior side walls of the tank 10, effectively continue to function as above described. Should the completed apparatus be turned upside down, that is, inverted from the position shown in Figure 1, the above-described isolating action against sound and vibration still takes place, it being noted that in that case the felt padding 23, interposed between the lower face of the block 20 and the upper face of the cover plate 22 of the upper frame member 13 provides the yielding and isolating

link through which the effective weight or load of the construction is transmitted to the casing itself. In fact, the construction will be seen to be such that the apparatus may be positioned at any angle without detracting from the isolating action above described.

Another advantage that I achieve by reason of the yielding action of the support for the condenser construction is that the various parts may freely expand or contract, due to temperature changes, any differences in the rates of expansion or contraction being effectively taken up by the yielding material forming part of the supporting structure; also, any possible stretching or distortion of the tank, due to the high pressure of gaseous dielectric therein, is prevented from affecting the structural interrelation of the parts inasmuch as the yielding material automatically compensates for any possible change in configuration or dimensions of the tank due to the high pressure therein.

Furthermore, it will be noted that the entire condenser construction is, in a sense, suspended centrally from substantially a single point, namely, at the intersection of supporting cross bars 17 and 18 (Figure 1); the condenser construction may freely move up and down by contraction or expansion without being interfered with by the sealed casing itself.

Considering now the coaction of the gaseous dielectric under a pressure on the order of fifteen atmospheres with certain other features of my construction, it might at this point first be noted that the gaseous dielectric under pressure, has a very high dielectric strength, much in excess of that of air or gases at atmospheric pressure. It vastly improves the insulation between opposed foil plate members, due to its sorption by the dielectric sheet material, such as paper sheets 51, that is interposed between adjacent foil plates; and by the relatively high pressure gas which occupies the spaces that exist between the fibres of this sheet insulation and between the latter and adjacent foil plates achieves vastly improved insulation. Such spaces, if filled with air or other gaseous dielectric at atmospheric pressure, would be overstressed due to dielectric flux refraction and due to the unequal voltage distribution across dielectrics of unlike permittivities (air and paper) in series multiple. For example, the permittivity of the paper is on the order of 3 or 4 and the permittivity of the air is about unity. The air at atmospheric pressure, a weak dielectric, would thus be made to assume 3 or 4 times the stress assumed by the paper and would readily break down and cause a puncture. However, such possible air spaces, in accordance with certain features of my invention, are filled with the gaseous dielectric under a pressure on the order of fifteen atmospheres and hence one whose dielectric strength is many times that of air at atmospheric pressure. The same above-mentioned dielectric stress is similarly divided between the paper and the gas under pressure inversely as their permittivities, the permittivity of the gas under pressure being about unity, but the gaseous dielectric under pressure, having a very high dielectric strength compared to that of air at atmospheric pressure, can safely assume three or four or more times the stress assumed by the paper, without break-down, and puncture is thus effectively prevented.

The gaseous dielectric under pressure thus penetrates and occupies all pores or spaces between

and about the adjacent foil plates and due to its high dielectric strength it can safely assume the higher voltage gradient that is imposed upon it due to dielectric flux refraction and the unequal voltage distribution across the serially related dielectric media of unlike permittivities; should, therefore, there be any relatively thin or weakened portions in the paper, such portions are greatly reinforced by the coaction therewith of the gaseous dielectric under pressure, the latter acting to cause the weaker or thinner portions of the paper dielectric to assume a much smaller fraction of the total stress than would otherwise be the case, and thus break-down and puncture is further prevented.

Due to other coactions of the gaseous dielectric under pressure, I am enabled, for a given configuration and volume of tank or container, to obtain a greater plate area at smaller spacing than would otherwise be possible. For example, the stacked condenser construction 12 must be insulated laterally from the supporting tie rods 15 and I am enabled vastly to diminish the spacing between the peripheral portions of the condenser 12 and the tie rods or bolts 15 by separating these parts by solid dielectric material in series with the gaseous dielectric under pressure, the latter having a greatly lower permittivity than the former.

As above described, the bolts 15 have strung thereupon and hence are covered by the solid dielectric tubes 25 and the solid dielectric supporting members 24. These solid dielectric members may be made of bakelite, whose permittivity is 5 or 6. The dielectric stress between the condenser 12 and the tie rods 15, the latter being at zero potential, divides itself inversely as the permittivity of the bakelite of the tubes 25 and the permittivity of the gaseous dielectric under pressure. The bakelite may thus be caused to assume only one-fifth or one-sixth of the total stress, the remaining relatively larger fraction being assumed by the gaseous dielectric under pressure which, as above noted, has a very high dielectric strength.

Due to this inter-relation of the parts, I am enabled to diminish the spacing between the peripheral portions of the condenser 12 and the tie bolts 15 or, for a given spacing of the tie rods 50, I am enabled to increase the area of the condenser plates very materially; due to this same coaction, I am enabled to use lesser thickness in solid dielectric material than would otherwise be the case, thus minimizing the weight and cost of construction and further diminishing the spacing.

Considering now the coaction of the gaseous dielectric under pressure with the solid dielectric supports 24, reference may first be made to Figure 4 of the drawings in which is shown on an enlarged scale the preferred shape that I give these supporting members 24. Each supporting member, made of solid dielectric material, such as molded bakelite, is shaped to extend laterally to a substantial distance to each side of the tie bolt 15 so as to provide in effect two laterally spaced condenser-engaging portions 24^a and 24^b.

By thus shaping the members 24, I am enabled to interpose between the bolt 15 and the condenser 12, at the point or points thereof most closely spaced, both solid dielectric material and the gaseous dielectric under pressure, thus achieving substantially similar advantages and actions as have been above described in connection with the solid dielectric tubes 25.

The above-described shaping of the supporting members 24 also makes it possible for me to interpose between the condenser 12 and the supporting bolts 15 a sufficient thickness of solid dielectric material alone, greater than the shortest distance between the bolt 15 and the condenser 12, adequately to withstand the dielectric stress therebetween while at the same time providing a sufficiently strong mechanical structure to withstand the mechanical stresses that might be imposed thereon. Furthermore, the possible leakage path from the condenser 12 to the rod 15 by way of any of the solid dielectric members 24 is thus made much longer than the shortest distance between these two parts and, due to the effect of the gaseous dielectric under pressure in vastly increasing the resistance of solid dielectric surface to surface leakage, I am enabled thus to avoid possible surface leakage as well.

As hereinbefore pointed out, the solid dielectric members 24 also support, by way of the ears 24^c and 24^d, the conductors that constitute the electrical connections of or with the condenser and discharge coil or coils. These connections may be widely varied but, for purposes of illustration, let it be assumed that the condenser units 12^a are connected in series in any suitable manner by way of the tabs above-described in connection with Figures 5 and 6, so that the apparatus may function on a single-phase circuit. Thus, conductor 105 30 leads from one of the high voltage terminals 28 down through the aligned ears 24^d of the solid dielectric supports 24 (see the left-hand portion of Figure 1) where it is connected, as by the device 60 to a tab G of the lowermost condenser unit 12^a while conductor 29 leads from the other high voltage terminal 28 to a tab C of the uppermost condenser unit 12^a. Thus, the serially connected condenser units may be connected to an outside circuit.

From the discharge coil or coils 28 (see bottom part of Figure 1) a conductor 61 connects one terminal thereof to the tab G of the lowermost condenser unit of the stack, while a conductor 62 leads from the other terminal of the discharge 120 coil or coils 28 through the aligned ears 24^c of the solid dielectric members 24 upwardly to the tab C of the uppermost condenser unit.

These various connections, it will be seen, can be readily made or installed before the otherwise assembled condenser construction, suspended from the cover member 11, is inserted into the tank or container 10.

The paper insulation 51, above-described in connection with Figures 5 and 6, constitutes a 130 preferred form of solid dielectric material and in connection with the above-described coaction between the gaseous dielectric under pressure and such paper insulation, I achieve that coaction with many other advantages if, as is preferably the case, I use uncalendered paper. Each paper member 51 (see Figure 6) may comprise several layers of uncalendered paper of suitable thickness and a feature of great advantage resides in the manner in which the foil plate members 140 become embedded in the uncalendered paper dielectric. This embedding action is clearly indicated in the exaggerated single view of Figure 6 from which it will be seen that, where the paper members 51 extend beyond the edges of 145 the foil members, the paper members 51 come into substantial contact and thus substantially close off that edge portion of the foil plate members against exposure. This feature makes it possible to use a greater area of foil members for 150

a given area of paper members since the substantial envelopment, by solid dielectric material, of the edge portions of the foil members, makes it unnecessary to make such provision for surface leakage as would otherwise be necessary.

It will thus be seen that there has been provided in this invention a condenser construction in which the several objects hereinabove noted, together with many thoroughly practical advantages, are successfully achieved. It will be seen that the construction is of a thoroughly practical nature, is of high capacity per unit volume, is well adapted to operate at and withstand relatively high potentials, and is noiseless in operation. It will be seen, moreover, that the apparatus is well adapted to meet the hard conditions of practical use.

As many possible embodiments may be made of the above invention and as many changes might be made in the embodiment above set forth, it is to be understood that all matter hereinbefore set forth, or shown in the accompanying drawings, is to be interpreted as illustrative and not in a limiting sense.

25 I claim:

1. In condenser construction, in combination, a tank having a flanged closure member, the flange of which is shaped to be received into the open end of said tank, said flange having a plurality of pairs of opposed openings, a plurality of bars carried by said closure member, one bar for each pair of openings and each bar having its ends seated in an opening in said flange, a block of solid material carried by said bars, a frame-like member extending crosswise of said tank and having a hollow portion in which said block is received but dimensioned so that said block is spaced from the walls of said hollow portion, a plurality of inter-leaved condenser plates suspended from said frame-like member, and yielding means interposed between said block and the walls of said hollow portion.

2. In condenser construction, in combination, a tank having a flanged closure member, the flange of which is shaped to be received into the open end of said tank, said flange having a plurality of pairs of opposed openings, a plurality of bars carried by said closure member, one bar for each pair of openings and each bar having its ends seated in an opening in said flange, a block of solid material carried by said bars, a frame-like member extending crosswise of said tank and having a hollow portion in which said block is received but dimensioned so that said block is spaced from the walls of said hollow portion, a plurality of inter-leaved condenser plates, means extending lengthwise of said tank and adjacent the inside walls thereof for suspending said plates from said frame-like member, yielding means in the space between said block and the walls of said hollow portion, and yielding means interposed between said suspension means and the wall of said tank.

3. In condenser construction, in combination, 65 a tank having a flanged closure member, the flange of which is shaped to be received into the open end of said tank, said flange having a plurality of pairs of opposed openings, a plurality of bars carried by said closure member, one bar for each pair of openings and each bar having its ends seated in an opening in said flange, a block of solid material carried by said bars, a frame-like member extending crosswise of said tank and having a hollow portion in which said block is received but dimensioned so that said block is

spaced from the walls of said hollow portion, a plurality of inter-leaved condenser plates, means extending lengthwise of said tank and adjacent the inside walls thereof for suspending said plates from said frame-like member, yielding means in the space between said block and the walls of said hollow portion, and a plurality of yieldable members carried by said suspension means for contacting with the inside walls of said casing.

4. In condenser construction, in combination, a tank having a flanged closure member, the flange of which is shaped to be received into the open end of said tank, said flange having a plurality of pairs of opposed openings, a plurality of bars carried by said closure member, one bar for each pair of openings and each bar having its ends seated in an opening in said flange, a block of solid material carried by said bars, a frame-like member extending crosswise of said tank and having a hollow portion in which said block is received but dimensioned so that said block is spaced from the walls of said hollow portion, a plurality of inter-leaved condenser plates, a plurality of rods extending lengthwise and exteriorly of said inter-leaved condenser plates for suspending the latter from said frame-like member, a plurality of yieldable members distributed lengthwise along said rods for contacting with the walls of said tank, and yielding means in the space between said block and the interior walls of said hollow portion of said frame-like member.

5. In condenser construction, in combination, a casing having a closure member adapted to be assembled with respect thereto; a condenser construction including a plurality of plates and means for holding the latter in assembled relation; means for suspending said condenser construction from said closure member so that the latter with the former may be assembled with respect to said casing; said suspending means being reconstructed so that said condenser construction may swing laterally; and yielding means interposed between said condenser construction and the walls of said casing for opposing swinging of said condenser construction.

6. In condenser construction, in combination, a casing having a closure member adapted to be assembled with respect thereto; a condenser construction including a plurality of plates and means for holding the latter in assembled relation; means yieldingly supporting said condenser construction from said closure member; and yielding means interposed between said condenser construction and the interior walls of said casing.

7. In condenser construction, in combination, a casing having a closure member adapted to be assembled with respect thereto; a condenser construction including a plurality of plates and means for holding the latter in assembled relation; and means for yieldingly suspending said condenser construction from said closure member.

8. In condenser construction, in combination, a casing; a condenser construction operating at power frequencies and including a plurality of plates and discharge coils connected thereacross; said discharge coils acting to dissipate any charge retained by said plates after the condenser is disconnected from its circuit and means for acoustically insulating said plates and said coils from said casing, thereby to prevent said plates and coils from causing vibration of said casing at an audio frequency rate.

9. In condenser construction, in combination, a

- and within said tank; and means interposed between said condenser construction and said tank construction preventing the transmission of audio frequency vibration from said plates to 5 said tank.
23. In condenser construction, in combination, a hermetically sealed tank construction, to withstand substantial pressures; a condenser construction, including a plurality of plates, within 10 said tank; a gaseous cooling and insulating medium under pressure and within said tank; and means yieldingly suspending said condenser construction within said tank and from an upper portion thereof and constructed so as to permit circulation of said gaseous medium into contact with the walls of said tank.
24. In condenser construction, in combination, a sealed casing; an electric condenser therein comprising alternated plate electrodes; a plurality of rods extending along said condenser for 20 supporting said condenser; and means including solid dielectric material and a gaseous dielectric under pressure arranged serially therewith for insulating said condenser from said supporting rods.
25. In condenser construction, in combination, a sealed casing; an electric condenser comprising foil plates alternated with solid dielectric material arranged therewith in a stack; a plurality of metallic tension members extending lengthwise of said stack for holding the latter in assembled relation; and means for insulating lateral portions of said condenser from said metallic means and comprising a gaseous dielectric under pressure and solid dielectric material arranged in series therewith.
26. In condenser construction, in combination, a casing; an electric condenser therein comprising a plurality of spaced plate electrodes arranged in spaced relation; metallic means for supporting said condenser; and means interposed between said condenser and said metallic means for steadyng the former against the latter, said interposed means including a solid dielectric member shaped to have a greater effective length than the shortest distance between said metallic means and said condenser.
27. In condenser construction, in combination, a sealed casing; an electric condenser therein comprising a plurality of spaced plate electrodes arranged in spaced relation; metallic means for supporting said condenser; means interposed between said condenser and said metallic means for steadyng the former against the latter, said interposed means including a solid dielectric member shaped to have a greater effective length than the shortest distance between said metallic means and said condenser; and a gaseous dielectric under pressure contacting the surface of 60 said interposed solid dielectric means.
28. In condenser construction, in combination, a casing; an electric condenser therein comprising a plurality of spaced plate electrodes arranged in spaced relation; metallic means for supporting 65 said condenser; and means interposed between said condenser and said metallic means for steadyng the former against the latter, said interposed means including a solid dielectric member shaped to provide a portion extending 70 toward said condenser along the shortest path therebetween but of a length less than said path and an effective condenser-engaging portion having a length greater than said path.
29. In condenser construction, in combination, 75 a sealed casing; an electric condenser therein comprising a plurality of spaced plate electrodes arranged in spaced relation; metallic means for supporting said condenser; means interposed between said condenser and said metallic means for steadyng the former against the latter, said interposed means including a solid dielectric member shaped to provide a portion extending toward said condenser along the shortest path therebetween but of a length less than said path and an effective condenser-engaging portion having a length greater than said path.
30. In condenser construction, in combination, a container having a plurality of rods extending thereacross and at an angle to each other, said rods being rigidly secured to said container; a condenser construction including a plurality of plates, a device having openings therein through which said rods pass; and means securing said condenser to said device.
31. In condenser construction, in combination, a container having a plurality of rods extending thereacross and at an angle to each other, said rods being rigidly secured to said container; a block supported by said rods substantially at the intersection thereof; and a condenser construction including a plurality of condenser plates and an end member having a seat for receiving said block.
32. In condenser construction, in combination, a container having a plurality of rods extending thereacross and at an angle to each other; said rods being rigidly secured to said container; a condenser construction including a plurality of condenser plates and having means related to said rods, each rod preventing movement of said condenser construction in a direction about the axis of another of said rods; and means interposed between said container and those portions of said condenser construction remote from said rods for opposing movement of said condenser construction relative to the container.
33. In condenser construction, in combination, a tank having a flanged closure member, the flange of which is shaped to be received into the open end of said tank, said flange having a plurality of pairs of opposed openings, a plurality of bars carried by said closure member, one bar for each pair of openings and each bar having its ends seated in an opening in said flange, and a condenser construction suspended from said bars, said condenser construction extending into said tank and said flange being received within the said end of said tank to an extent sufficient to cause the walls of said tank adjacent said end to close over the openings in said flange.
34. In condenser construction, in combination, a tank having a flanged closure member, the flange of which is shaped to be received into the open end of said tank, said flange having a plurality of pairs of opposed openings, a plurality of bars carried by said closure member, one bar for each pair of openings and each bar having its ends seated in an opening in said flange, a condenser construction suspended by said bars and extending downwardly into said tank, said flange being received within the open end of said tank to an extent sufficient to cause the walls of the latter to close over said opposed openings, and means sealing the walls of said tank to said closure member at points above said openings.
35. In condenser construction, in combination, a

1. tank having a flanged closure member, the flange of which is shaped to be received into the open end of said tank, said flange having a plurality of pairs of opposed openings, a plurality of bars carried by said closure member, one bar for each pair of openings and each bar having its ends seated in an opening in said flange, a condenser construction suspended by said bars and extending downwardly into said tank, said flange being

interposed means including a solid dielectric member shaped to have a greater effective length than the shortest distance between said metallic means and said condenser, and supporting means interposed between the inner wall of said casing and said member. 80

16 received within the open end of said tank to an extent sufficient to cause the walls of the latter to close over said opposed openings, and the free walls of said tank about the otherwise open end thereof being welded to said closure member along a line above said openings in the flange of said closure member.

41. In condenser construction, in combination, a sealed casing; an electric condenser therein comprising alternated plates; a plurality of metallic members extending lengthwise of said condenser for supporting the latter within said casing; means including solid dielectric material and a gaseous dielectric under pressure arranged in series with said solid dielectric material for insulating said condenser from said metallic members, said solid dielectric material having a plurality of recesses exposed toward said casing; and means seated in said recesses and engaging the wall of said casing for spacing said condenser from said casing. 85

20 36. In condenser construction, in combination, a tank having a flanged closure member, the flange of which is shaped to be received into the open end of said tank, said flange having a plurality of pairs of opposed openings, a plurality of bars carried by said closure member, one bar for each pair of openings and each bar having its ends seated in an opening in said flange, a condenser construction, and means including a member interlocked with said bars for suspending said condenser construction from said bars.

42. In condenser construction, in combination, a sealed casing; a condenser construction therein; means including a metallic member extending lengthwise of said condenser construction for supporting the latter within said casing, said 100 metallic member being spaced from said condenser construction; insulating means for insulating said metallic member from said condenser construction and including solid dielectric material and a gaseous dielectric under pressure, both 105

25 arranged in the space between said condenser construction and said metallic member and arranged in series with one another, said solid dielectric material being in the form of sleeve-like members strung onto said metallic member; and 110 means interposed between the wall of said casing and one of said sleeve-like members for giving said metallic member a support against the wall of said casing, said sleeve-like member and said 30 interposed means being shaped to interfit. 115

35 37. In condenser construction, in combination, a tank having a flanged closure member, the flange of which is shaped to be received into the open end of said tank, said flange having a plurality of pairs of opposed openings, a plurality of bars carried by said closure member, one bar for each pair of openings and each bar having its 40 ends seated in an opening in said flange, a block supported by said bars and having openings through which said bars pass, a condenser construction including a plurality of condenser plates and suspension members for said plates, and means to which said suspension members are connected and having a seat for receiving said block.

38. In condenser construction, in combination, a sealed casing; an electric condenser comprising foil plates alternated with solid dielectric material arranged therewith in a stack; a plurality of metallic tension members extending lengthwise 120 of but spaced from said stack for holding the latter in assembled relation; means for insulating lateral portions of said condenser from said metallic means and comprising a gaseous dielectric under pressure and solid dielectric material arranged in series therewith, said solid dielectric material being in the form of tubes strung onto said metallic tension members; and a solid dielectric member interposed between the adjacent ends of two of said tubes and engaging both the 125 side of said stack and the inside wall of said casing. 130

45 39. In condenser construction, in combination, a casing, an electric condenser therein comprising a plurality of spaced plates, metallic means for supporting said condenser, means interposed between said condenser and said metallic means for steadyng the former against the latter, said interposed means including a solid dielectric member shaped to have a greater effective length than the shortest distance between said metallic means and said condenser, said member having a recess exposed toward said casing, and yielding means seated in said recess and interposed between said member and the wall of said casing. 135

50 40. In condenser construction, in combination, a casing, an electric condenser therein comprising a plurality of spaced plates, metallic means for supporting said condenser, means interposed between said condenser and said metallic means for steadyng the former against the latter, said

44. In condenser construction, in combination, a metallic casing; a condenser construction operating at commercial power frequencies and including a plurality of opposed plate members; and yielding means incapable of per se vibrating at audio frequency interposed between said condenser construction and said metallic casing for acoustically insulating the latter from the former. 140

55 45. In condenser construction, in combination, a casing; a condenser construction including a plurality of opposed plate members; and means for supporting said condenser construction internally of said casing, said means including yieldable means incapable per se of acoustic vibration for preventing the transmission of audio frequency vibrations from said condenser construction to said casing. 145

60 70 46. In condenser construction, in combination, a casing, an electric condenser therein comprising a plurality of spaced plates, metallic means for supporting said condenser, means interposed between said condenser and said metallic means for steadyng the former against the latter, said

46. In condenser construction, in combination, 150

- a casing; an electric condenser therein comprising metal foil plates alternated with solid dielectric material arranged therewith to form a stack; two pressure plates, one at each end of said stack; a plurality of metallic tension members spaced about said stack and extending between said pressure plates; and solid dielectric means interposed between and in engagement with intermediate portions of said stack and said tension members to prevent movement of intermediate portions of said stack out of alignment with the axis of the latter.
47. In condenser construction, in combination, a casing; an electric condenser therein comprising metal foil plates alternated with solid dielectric material arranged therewith to form a stack; two pressure plates, one at each end of said stack; a plurality of metallic tension members spaced about said stack and extending between said pressure plates; and solid dielectric means about said tension members having portions thereof in engagement with intermediate parts of said stack, thereby to prevent said parts of said stack from moving out of alignment with the axis of the latter.
48. In condenser construction, in combination, a cylindrical tank; an electric condenser therein comprising foil plates alternated with solid dielectric material and arranged in a stack whose axis is substantially coincident with the axis of said tank, said stack being substantially square in cross-section; two pressure plates, one at each end of said stack; a plurality of metallic rods extending along but spaced from the sides of said stack and coacting with said pressure plates to hold said stack in compression; and means for insulating said metallic rods from said condenser and comprising a gaseous dielectric under pressure and solid dielectric material arranged in series therewith.
49. In condenser construction, in combination, a cylindrical tank; an electric condenser therein comprising foil plates alternated with solid dielectric material and arranged in a stack whose axis is substantially coincident with the axis of said tank, said stack being substantially square in cross-section; two pressure plates, one at each end of said stack; a plurality of metallic rods extending along but spaced from the sides of said stack and coacting with said pressure plates to hold said stack in compression; and a plurality of members interposed between and in engagement with said rods and intermediate portions of said condenser stack for preventing movement of said portions out of alignment with the axis of said stack.
50. In condenser construction, in combination, a cylindrical tank; an electric condenser therein comprising foil plates alternated with solid dielectric material and arranged in a stack whose axis is substantially coincident with the axis of said tank, said stack being substantially square in cross-section; two pressure plates, one at each end of said stack; a plurality of metallic rods extending along but spaced from the sides of said stack and coacting with said pressure plates to hold said stack in compression; a plurality of solid dielectric members strung along said rods and engaging the sides of said stack to prevent intermediate portions of the latter from moving out of alignment with the axis of said stack; and solid dielectric tubular members strung onto said rods and alternated with said solid dielectric members for holding the latter spaced lengthwise along said rods.
51. In condenser construction, in combination, a cylindrical tank; an electric condenser therein comprising foil plates alternated with solid dielectric material and arranged in a stack whose axis is substantially coincident with the axis of said tank, said stack being substantially square in cross-section; two pressure plates, one at each end of said stack; a plurality of metallic rods extending along but spaced from the sides of said stack and coacting with said pressure plates to hold said stack in compression; a plurality of solid dielectric members strung along said rods and engaging the sides of said stack to prevent intermediate portions of the latter from moving out of alignment with the axis of said stack; solid dielectric tubular members strung onto said rods and alternated with said solid dielectric members for holding the latter spaced lengthwise along said rods, said parts being so proportioned that there is a space between said solid dielectric tubular members and the sides of said stack; and a gaseous dielectric under pressure filling said space and being thereby arranged in series with said solid dielectric tubular members for coaction therewith in insulating said stack from said rods.

FRANKLIN S. SMITH.
